UNITED STATES PATENT OFFICE.

GUSTAV A. HUBEN, OF CHICAGO, ILLINOIS.

DESIGN FOR A RUBBER HEEL.

52,137.

Specification for Design.

Patented July 2, 1918.

Application filed March 5, 1918. Serial No. 220,662. Term of patent 7 years.

To all whom it may concern:

Be it known that I, GUSTAV A. HUBEN, a citizen of the United States of America, residing at Chicago, in the county of Cook and State of Illinois, have invented a new, original, and ornamental Design for Rubber Heels, of which the following is a specification, reference being had to the accompanying drawing, forming a part thereof.

The figure is a perspective view of a rubber heel illustrating my new design.

I claim:

The ornamental design for a rubber heel, as shown.

GUSTAV A. HUBEN.
